UNITED STATES PATENT OFFICE.

ALBERT BROWN AND ROBERT G. PECK, OF CHICAGO, ILLINOIS, ASSIGNEES TO THE ARIDOR COMPANY, OF CHICAGO, ILLINOIS, A CORPORATION OF ILLINOIS.

DISPLAY RECEPTACLE.

Application filed January 11, 1924. Serial No. 685,535.

The present invention aims to provide an improved receptacle particularly adapted, for example, for use as a display receptacle for hard candies.

5 For illustration, one desirable form of display receptacle containing an embodiment of the invention is shown in the annexed drawings, by reference to which the invention will be readily understood.

10 In said drawings:

Figure 1 is a side elevation of the illustrative receptacle.

Fig. 2 is a side elevation of the mouth of the receptacle with its door or closure in 15 open position.

Fig. 3 is an inner face view of the receptacle closure as viewed on line 3—3 of Fig. 4, showing the mouth of the receptacle in cross section.

20 Fig. 4 is a horizontal plan section through the mouth of the receptacle and its closure.

Figs. 5 and 6 represent details of construction of the specific closure shown.

The illustrative embodiment of the invention shown in the drawings is a transparent receptacle for use on a store counter for displaying contents such, for example, as hard candies. The receptacle is shown having a front display end, while the rear end 30 of the receptacle may be opened to permit insertion of a candy scoop for dispensing the candy to customers.

Said receptacle is represented as a jar 1 of transparent glass, arranged in recumbent position, and formed to provide a display head 2 of extensive surface at the end of the jar opposite its mouth.

By supporting the neck 3 of the jar in a rack or stand 4, the jar is held at an appropriate inclination to cause the candies there-in to gravitate toward and remain massed in the space adjacent the display head 2, through which, as well as through the transparent top and sides of the receptacle, the 45 candies are exposed to the view of customers standing before the counter on which the receptacle is placed.

The mouth of the receptacle is closed by a door 5, herein represented as a hinged jar cap 50 provided with a compressible gasket 6 of rubber or other suitable material formed and positioned within the door to engage the annular rim of the open end of the jar in a

manner to maintain a tight closure. The gasket may be held in place within the cap 55 by an annular flange 7. In this instance the door or jar cap is self-opening by the action of a spring-hinge 8. It is held closed by the action of the gasket 6 which, in the present instance, is shown as provided with an annular wall portion 9 and an inwardly extending transverse flange 10. The inner face of the annular wall 9 of the gasket is of convex form in cross section, while the outer face of the wall is of concave form, the latter forming in effect a broad annular groove on the outer face of the gasket and, when the gasket is placed within the door or jar cap 5, provides an annular hollow space between the outer face of the gasket 70 and the inner annular face of the door.

The mouth or rim of the open end of the jar is shown as provided with a narrow annular flange or flattened bead 11. The gasket 6, in the form shown, will occupy 75 normally the position shown in dotted lines in Fig. 4, but when the door is closed, the inside diameter of the gasket being somewhat less than the outside diameter of the jar rim, the gasket, by reason of its resiliency, will be forced or bulged outwardly into the hollow space above referred to, and by reason of its tendency to assume its normal position and form, will grip the rim of the jar with sufficient force to resist the opening 80 action of the spring-hinge 8 and provide a substantially air-tight closure between the door and jar. The door-opening action of the spring-hinge 8 will be further resisted by the gasket passing over and 85 assuming a position in back of the flange or bead 11 of the rim, as shown in full lines in Fig. 4.

It will be observed that to open the door it is necessary to disengage the gasket from 90 the mouth of the jar, after which the spring-hinge 8 will act to swing the door outwardly to its wide-open position, as shown by dotted lines in Fig. 4.

The hinge on which the door 5 is mounted 100 is shown attached to a collar 12 surrounding and affixed to the neck of the jar. This collar may be an integral part of the rack or stand 4, which may be formed as a plate of sheet metal having an opening to receive the 105 neck of the jar. A number of fingers 13 (in

the present instance three) may be secured to or formed integral with the collar 12 and positioned to extend laterally therefrom in a manner to engage a number of spring fingers 14 secured to or formed integral with a band or ring 15 adapted to surround the neck portion of the jar and be secured thereto in any suitable manner, as by means of the bolt 16 and nut 17 connecting the adjacent ends of the band in a manner to draw the band tightly around the neck of the jar. Thus the metallic stand with the door carried thereby may be conveniently applied to the jar by inserting the open end or neck portion of the jar into the opening of the collar 12 and pressing the fingers 13 into engagement with the spring fingers 14, as shown in Figs. 1, 2 and 4.

Hard candies when exposed to humidity become sticky and dull looking. To maintain an attractive display, the candies should be kept dry and crisp, in order to preserve their solidity, color and glint or lustre, and to prevent objectionable sticking of the candies to one another or to the interior surfaces of the display receptacle. Such a display may be maintained in the illustrative receptacle, the interior and contents of which are maintained in dry condition by the action of a hygroscopic medium represented by a pad or cake 18 (Fig. 4) of porous moisture absorbing and attracting material, e. g., a baked mass of infusorial earth impregnated with calcium chloride and containing asbestos fibers as a binding material.

The hygroscopic pad 18 is shown mounted in the jar closure or door 5, being fitted in a chamber formed of a housing 19 which, in the form shown, comprises a cup-shaped member, stamped from aluminum or other suitable material, and having a plate 20 affixed thereto in any suitable manner, as, in the present instance, by the ears 21 extending through apertures in the plate and bent over to hold the parts securely together.

The plate 20 may extend beyond the periphery of the housing and with the pad mounted therein may be secured removably within the door 5 between a shoulder 22 of the door or closure and the gasket 6, the latter being held against accidental displacement by the flange 7. A bolt 23 passing through a central hole in the hygroscopic pad centers the pad in its chamber in a manner to prevent contact of the pad with the housing and provide free air space around the periphery of the pad.

Through a series of perforations 24 in the housing 19, the air in the display receptacle may circulate through the hygroscopic pad chamber in contact with and through the pores of the hygroscopic substance, which will attract and absorb any moisture in the receptacle and keep its contents thoroughly dry. The pad may advantageously be posi-

tioned a suitable distance from the perforated side of the housing 19 to provide a free air space along the entire inner side of the pad, thus permitting the air of the receptacle to circulate freely within the housing and in contact with a very large portion of the surface of the pad. To provide for such positioning of the pad, the bolt 23 may be formed with a reduced portion where it passes through the pad and with a shoulder 25 by which the pad may be held in spaced relation with reference to the perforated side of the housing.

By locating the hygroscopic pad adjacent the mouth of the display receptacle, it may exercise its dehydrating action at the most advantageous point, i. e., at the end of the receptacle remote from the display end and which is first affected by the admission of atmospheric moisture. 85

Associated with the perforated side of the housing 19 is a shutter represented as a plate 26 having perforations 27 normally in register with those of the housing 19 but adapted to be moved out of register therewith. This shutter plate is shown mounted on the central post or bolt 23 in a manner to rotate therewith, and the bolt is shown rotatably mounted, adjacent its opposite ends, in the housing 19 and plate 20. The shutter, in the present instance, is fitted adjacent the inner perforated face of the housing 19 and forms in effect the inner side of the door or closure 5.

When the receptacle door is opened, the shutter 26 is turned to the position shown in Fig. 2 moving its openings or perforations out of register with those of the housing 19 so as to close the hygroscopic pad chamber. This is accomplished by means 105 represented by a flat spring 28 rigidly secured at one end to the plate 20 and provided at its opposite end with a laterally extending portion 29. The portion 29 of the spring 28 is provided with an inclined cam 110 slot 30 (Figs. 5 and 6) for receiving the outer end of an arm 31, the opposite or inner end of which is secured to the central post or bolt 23, as is also the shutter 26. The tendency of the spring 28 is to occupy a 115 position substantially parallel with and adjacent the plate 20, as shown in the open or dotted line position of the door in Fig. 4 at which time the outer end of the arm 31 will occupy a position in the end of the cam 120 slot 30 adjacent the spring 28 as shown in Fig. 6, and the apertures of the housing 19 and shutter 26 will be out of register with each other, as shown in Fig. 2.

Upon closing the receptacle door, the 125 shutter plate 26 is restored to the normal position shown in Fig. 3, with its perforations registering with those of the housing 19, thus reopening the hygroscopic pad chamber to communication with the interior of the dis- 130

play receptacle. The means shown for this purpose comprises a foot 32 extending laterally from the portion 29 of the spring 28. This foot 32, when the door is closed, engages the rim of the jar, and the portion 29 is forced outwardly against the action of the spring 28 to the position shown in Figs. 4 and 5, thereby causing the outer end of the relatively inflexible arm 31 to assume a position in the opposite end of the slot 30, as shown in Fig. 5.

The outer end of the arm 31, in changing its position from one end of the slot to the other, is swung laterally of the spring 28 and relative to the housing 19, thus rocking the bolt 23 and shutter 26 to bring the perforations of the housing 19 and the shutter 26 into register and establishing communication between the hygroscopic pad chamber and the interior of the display receptacle.

To provide for the free action of the shutter-operating parts, the flange 10 of the gasket and the plate 20 may be cut away as indicated at 33 and 34 respectively in Figs. 2 and 3.

From the foregoing description, it will be observed that the chamber containing the hygroscopic pad is automatically closed when the receptacle door is opened, and is reopened to communication with the interior of the receptacle when the door is shut. Thus, while the receptacle is open for dispensing candy, the hygroscopic pad is protected from absorption of atmospheric moisture, retaining its strength and efficiency to restore effective dehydrating conditions in the receptacle after it is closed. In other words, the action of the hygroscopic medium is exerted only upon the volume of air admitted to the receptacle itself. This promotes rapid and thorough dehydration, the action of the hygroscopic pad being unimpeded by surplus moisture absorption. Furthermore, by protecting the hygroscopic pad from moisture absorption other than that in the air admitted to the receptacle, the pad may be used for a prolonged period without becoming sufficiently wet to require replacement by a dry pad.

The construction described provides a practicable, convenient and attractive receptacle appropriate for a bright display of colored hard candies, for instance, and which may be opened from time to time for dispensing the candy while still effectively maintaining the efficiency of the receptacle to preserve the candies in dry and lustrous condition as is necessary for an attractive display.

Obviously the present invention is not limited to the particular embodiment thereof herein shown and described, since details of construction, form and arrangement may be modified. Moreover it is not indispensable that all the features of the invention be used

conjointly, since they may be advantageously used in various different combinations and sub-combinations.

Having described our invention, we claim:

1. A display receptacle comprising, in combination, a transparent container for displaying an enclosed mass of hard candies; a door for opening and closing the receptacle; a hygroscopic medium protected from the atmosphere while the receptacle is open and communicating with the interior of the receptacle when closed, for conditioning the interior of the receptacle to keep the candies dry and glistening for effective display; and means including a device actuated by engagement with the receptacle for placing said medium in communication with the interior of the receptacle when the same is closed.

2. A candy display receptacle comprising, in combination, an elongated substantially horizontal container having a display end; a closure therefor at the opposite end; hygroscopic material mounted proximate said closure; means protecting said material from exposure to the atmosphere when said closure is open; and means actuated by engagement with the mouth of the container to move said protecting means so as to expose said material to communication with the interior of the receptacle when the closure is shut.

3. A display receptacle comprising, in combination, a recumbent transparent jar having a display end; a band affixed to the jar; a collar removably connected to said band and having a rest by which the jar is supported at an inclination; a door provided with a hygroscopic medium hinged to said collar; means for excluding said medium from the atmosphere when the door is open; and means actuated by engagement with the rim of the jar to operate said first mentioned means to expose said medium to communication with the interior of the receptacle when the door is closed.

4. A display receptacle comprising, in combination, a recumbent transparent jar having a display end; a band removably affixed to the neck of the jar and having resilient means associated therewith; a collar provided with a rest for supporting the jar at an inclination and having means cooperable with said resilient means to connect removably the collar to said band; a door provided with a hygroscopic medium hinged to said collar; and self-contained means for housing said medium and automatically covering and uncovering the medium when the door is open and shut respectively.

5. A receptacle comprising, in combination, a container having a closure, said closure having a chamber for a hygroscopic medium open to the circulation of air; a shutter associated with said chamber; and

means operatively connected with said shutter to operate it to close the chamber when the closure is removed and actuated by engagement with the rim of the container to open the chamber when the closure is in place.

6. A display receptacle comprising, in combination, a transparent container; a closure therefor having a housing for hygroscopic material and open to the circulation of air; a shutter associated with said housing; an arm connected with said shutter; and means operatively connected with said arm in a manner to move said shutter in a direction to close said housing when the closure is open and actuated by engagement with the rim of the container to move said shutter in a direction to open said housing to the circulation of air in the receptacle when the closure is shut.

7. A display receptacle comprising, in combination, a transparent container; a hinged door or closure therefor; door opening means associated therewith; a hygroscopic medium proximate said door; means for excluding said medium from the atmosphere when the door is open and to exposing said medium to communication with the interior of the receptacle when the door is closed; a gasket mounted in said door; and means associated with the mouth of the receptacle and cooperable with said gasket to establish a tight closure between the door and receptacle and to resist releasably the action of said door opening means.

8. A receptacle comprising, in combination, a container; a closure therefor; a hygroscopic medium mounted proximate said closure; means for protecting said material from the atmosphere when the closure is removed; means including a device actuated by engagement with the mouth of the container to operate said protecting means to expose said medium to communication with the interior of the receptacle when the closure is in place; a gasket mounted in said closure; and means associated with the mouth of the container and cooperable with said gasket for securing removably the said closure to the container.

9. A display receptacle comprising, in combination, a transparent container; a closure therefor having a housing for hygroscopic material and open to the circulation of air; a shutter rotatably mounted on said housing; an arm connected with said shutter; resilient means mounted on said housing and having a slot for receiving one end of said arm in a manner to rotate said shutter in one direction to close the housing when the closure is open and in the opposite direction to open the housing when the closure is shut; and means cooperable with the rim of the container for actuating said resilient means.

10. A display receptacle comprising, in combination, a transparent container; a closure therefor; a housing for hygroscopic material and having perforations therein; means for holding said material in spaced relation with the perforated portion of the housing; a perforated shutter cooperable with the perforated portion of the housing; and means to operate said shutter for positioning the respective perforations of the shutter and housing out of register when the closure is open and including a device actuated by engagement with the rim of the container to operate said shutter to place the respective perforations in register when the closure is shut.

11. In a display receptacle, the combination with a removable closure, of a chamber for hygroscopic material communicable with the interior of the receptacle; a shutter closing said chamber when the closure is open; and means carried by the closure and operated by engagement with the receptacle to operate said shutter to open said chamber when the closure is shut.

12. In a display receptacle, the combination with a removable closure, of a gasket in the closure engageable with the mouth of the receptacle in a manner to secure the closure tightly in place; and means in the closure actuated by shutting the same to expose hygroscopic medium to the interior of the receptacle.

13. A receptacle having, in combination, a closure; a chamber for hygroscopic material in the closure; means in the closure to open and close said chamber; and an actuator for said last named means also contained in the closure and operated by engagement with the receptacle to effect closing of said hygroscopic chamber.

14. A receptacle closure containing a hygroscopic medium protected from atmospheric exposure and having self-contained means including a part operated by engagement with a receptacle to which the closure is applied to effect exposure of said medium to the interior of the receptacle.

15. A receptacle closure containing a hygroscopic medium protected from atmospheric exposure and having self-contained means operated by application of the closure to a receptacle to effect exposure of said medium to the interior of the receptacle, and also having in said closure a gasket surrounding said self-contained means and cooperable with the receptacle to seal the closure.

16. A receptacle closure containing a hygroscopic medium protected from atmospheric exposure and having self-contained means operated by application of the closure to a receptacle to effect exposure of said medium to the interior of the receptacle, and also having in said closure an

annular inwardly bulging gasket surrounding said self-contained means and adapted to embrace compressibly the neck of the receptacle.

5 17. A receptacle closure having a hygroscopic medium protected from atmospheric exposure and self-contained means operated by application of the closure to a receptacle to effect exposure of said medium to the interior of the receptacle.

10 18. A receptacle closure having a hygroscopic medium, means shutting off said medium from the air when the closure is not on the mouth of its receptacle, and

means engageable with such receptacle when the closure is applied thereon to operate said shutting off means to expose said medium in the receptacle.

15 19. A receptacle closure having a hygroscopic medium and equipped with a means movable to and from position to shut off said medium from the air and a means engageable with the receptacle controlling the action of said shut-off means.

20 In testimony whereof, we have signed our names to this specification.

ALBERT BROWN.
ROBERT G. PECK.
